UNITED STATES PATENT OFFICE.

JOHN RUSSELL ROACH, OF CALE, INDIANA, ASSIGNOR OF ONE-HALF TO JOHN M. BALE, OF BEDFORD, INDIANA.

FENCE-POST OR TELEPHONE-POLE.

No. 856,725

Specification of Letters Patent.

Patented June 11, 1907.

Application filed October 15, 1906. Serial No. 339,049.

To all whom it may concern:

Be it known that I, JOHN RUSSELL ROACH, a citizen of the United States, residing at Cale, in the county of Martin and State of Indiana, have invented a new and useful Improvement in Fence-Posts or Telephone-Poles, of which the following is a specification.

This invention relates generally to fence posts although it can be used equally as well for telephone or telegraph pole, the object of the invention being to provide a strong and durable sheet metal post formed from a single piece and provided with means for receiving and holding strands of wire.

Another object of my invention is to provide a brace which is adapted to be interlocked with the base of the post and serve to securely hold the same in an upright position.

With these objects in view, the invention consists essentially in forming a post from a single blank of sheet metal, said blank being rolled to substantially cylindrical form, one edge overlapping, said overlapping edge being apertured and slit for the purpose of receiving and securing the wire strands, the base portion of the blank being split, thereby providing two sections, each section being flanged for the purpose of re-inforcing the lower end of the post, and the extreme end of the lower end being bent outwardly to provide a base.

The invention consists also in providing a sheet metal brace having a dove-tail head adapted to interlock with the lower portion of the post and also having a base or foot piece.

The invention consists also in certain features of construction and novelties of combination all of which will be fully described hereinafter and pointed out in the claims.

In the drawings, Figure 1 is a view showing the base portion and brace of the post arranged beneath the surface of the earth and the strands of wire connected to the post.

Fig. 2 is a detail perspective view showing the post arranged for attachment to any fixed or solid object, the wire being disconnected therefrom. Fig. 3 is a top plan view of the post. Fig. 4 is a sectional plan view showing the manner of connecting the brace to the base portion of the post. Fig. 5 is a detached view showing the position of the

parts before the wire is fastened. Fig. 6 is a view showing the position of the parts after the wire has been fastened. Fig. 7 is a detail perspective view showing the edge. Fig. 8 is a plan of the blank from which the post is made. Fig. 9 is a view of the blank from which the brace is made.

As before stated my invention is especially adapted to fence posts and in Fig. 1, I have shown the preferred form of fence post. It will also be understood that this post can be arranged upon houses and similar structures and will serve all the purposes of a telephone or telegraph pole.

In carrying out my invention so as to produce either a fence post or telephone pole, I employ a blank A of sheet metal of suitable dimensions and roll the same longitudinally so as to provide a tubular post B, having a longitudinally projecting edge C which is apertured at regular intervals as shown at C' and slit as shown at C², thereby providing a tongue or finger C³. This tongue or finger C³, is usually bent out as shown in Figs. 5 and 6 so as to permit the wire strands D to be inserted in the aperture C' and then the tongue or finger C³, is bent back into the position shown in Fig. 6 thereby securely fastening the wire to the post. The lower portion of the blank is split longitudinally as shown at E thereby providing two base portions E', the edges of which are upset or bent outwardly thereby producing re-inforcing ribs or flanges and the extreme lower end of each base portion is bent outwardly in a horizontal direction as shown at E² thereby providing a firm base for the post to rest upon. These feet or base portions E², are apertured as shown at E³ through which spikes can be driven whenever it is desired to fasten the post to any object.

F indicates the brace which has a dove-tail head F', which is adapted to fit into the split portion of the base of the post and this brace is also provided with a foot portion F² and in practice I prefer to corrugate the brace longitudinally as shown at F³, for the purpose of strengthening the same. The foot piece F², is also provided with apertures F⁴, through which spikes can be driven if desired.

After the post is rolled or shaped into the form shown in Fig. 1, the brace can be equally and easily connected or dis-connected.

ed as desired. Ordinarily, if the device is used as a fence post the brace is attached thereto and the hole is large enough to receive both the base portion and the brace as most clearly shown in Fig. 1 and the entire base portion and brace are completely covered with earth. The wires are connected as already explained and whenever it is desired to disconnect any wires it can be accomplished by opening the slot as shown in Fig. 7. When the device is used as a pole for telephones or otherwise, all the parts are securely spiked to any fixed object.

It will thus be seen that I provide an exceedingly cheap, simple and durable form of post employed to carry out all the objects hereinbefore referred to.

Having thus fully described my invention, what I claim as new and desire to secure by Letters Patent, is:—

1. A tubular post formed from a single piece of sheet metal and having longitudinally projecting edge, said edge being aper-

tured and slotted, the lower portion of the post being bifurcated, each member having 25 re-inforced flanges and laterally projecting base portions, and a member having a head portion adapted to engage the bifurcated head portion of the post substantially as described.

2. A fence post formed from a single piece of sheet metal tubular in form having a longitudinally projecting edge, said edge being apertured and slotted as described, lower portion of the post being bifurcated, each 35 member having re-inforcing flanges and a laterally projecting base portion, said base portion being apertured and a brace having a dove-tail head and an apertured base all arranged and adapted to operate substantially 40 as set forth.

JOHN RUSSELL ROACH.
